W. S. REA.
APPARATUS FOR FORMING CONTAINERS FROM FIBROUS SUBSTANCES.
APPLICATION FILED JUNE 21, 1918.

1,279,586.

Patented Sept. 24, 1918.

UNITED STATES PATENT OFFICE.

WILLIAM S. REA, OF SAN FRANCISCO, CALIFORNIA.

APPARATUS FOR FORMING CONTAINERS FROM FIBROUS SUBSTANCES.

1,279,586.

Specification of Letters Patent. Patented Sept. 24, 1918.

Application filed June 21, 1918. Serial No. 241,252.

To all whom it may concern:

Be it known that I, WILLIAM S. REA, a citizen of the United States, and a resident of the city and county of San Francisco and State of California, have invented an Improvement in Apparatus for Forming Containers from Fibrous Substances; and I do hereby declare the following to be a full, clear, and exact description of my invention, such as will enable others skilled in the art to which it appertains to make and use the same.

This invention relates to an apparatus for forming containers from fibrous materials, such as wood or paper pulp and the like; and it consists in the novel construction, combination, and arrangement of parts as hereinafter described and later claimed.

The object of my invention is to provide an apparatus, which, by reason of its simplicity of construction and mode of operation, will make possible the manufacture of such containers with rapidity and accuracy, and at a low manufacturing cost.

In order that my invention may be clearly understood and readily carried into effect, the same is described with reference to the accompanying drawings, in which similar numerals indicate like parts:

Figure 1, is a view of the pulp mixture trough.

Fig. 2, is an elevation of the device in closed position,—the mold portion thereof being in section.

Fig. 3, is a side elevation of Fig. 2, looking from the right.

Fig. 4, is a detail showing mounting of porous mold.

In detail, my construction is as follows:

The fibrous pulp to be converted into containers is held in a suitable trough, 2, in which water, from any suitable source of supply, and dry pulp, fed into the trough through the feed-pipe, 3, connecting with a suitable storage tank (not shown in the drawings), are agitated and mixed by any suitable means (not shown in the drawings) until the desired consistency has been attained.

The containers are formed in a separable porous mold by the action of compressed air. Said mold is comprised of two parts, 4 and 5, suitably mounted on the inner surfaces of a series of longitudinal and latitudinal bands, 6, rigidly affixed by means of inwardly projecting lugs, 7, to the semi-cir-

cular jaws of a tong-like portable frame comprised of two parts, 8 and 9, pivotally held together by the pivot-pin, 11, engaging the slots, 10. Said frame is provided with handles, 12 and 13. Said bands, 6, are sharply tapered at their point of contact with the mold sections in order to avoid obstructing the pores in the mold as little as possible. Between the parts, 8 and 9, of the frame is mounted a compression spring, 14, which causes the mold to stand slightly open when not in use because of the play afforded by the slots, 10, which engage the said pivot-pin, 11.

Parallel with the handle, 13, and attached thereto by means of clamps, 15, is a flexible pipe, 16, connecting at the rear with a suitable air-compressor (not shown in the drawings) and adapted to be received by a nozzle, 17, suitably mounted on the right-hand jaw of said frame. The said nozzle opens into said mold through the boss, 18, supported by one of said bands, 6. By means of a trigger, 19, I operate the quick-acting valve, 20, which controls the supply of compressed air admitted into the mold during the formation therein of the said containers.

My apparatus is operated as follows: Pulp having been prepared in the trough, the operator opens the porous mold carried by the portable frame by forcing the handles apart; he then dips the open mold into the pulp mixture and fills the same with said mixture by pressing the handles together thereby closing the mold. The mold thus filled is then raised and held in a closed position by pressure exerted against the handles by the operator. He then operates the trigger valve and establishes connection between the mold and the air compressor. The force imparted by the compressed air thus let into the mold through the flexible pipe forces the pulp held in the mold against the inner surfaces of the porous mold in an even layer. The air also forces the water held in the moistened pulp mixture out through the pores in the mold surface. The air is then shut off by releasing the trigger. As the operator opens the mold preparatory to discharging the container thus produced, the action of the compression spring forces the two sides of said mold slightly apart by reason of the play afforded by the slots in the said frame, and in manner any pulp particles in the finished container which may have become embedded in the openings of the porous mold

during the time of its construction are dislodged from the said mold.

Having thus described my invention, what I desire to claim and to secure by Letters 5 Patent, is:

1. In an apparatus of the character described, a portable frame consisting of sections pivoted together at their central portions, a sectional porous mold suitably 10 mounted on said frame and adapted to open and close, means for forming fibrous containers in said mold by the action of compressed air, and means for discharging finished containers from said mold.
- 15 2. In an apparatus for forming fibrous containers by the action of compressed air, a portable sectional frame pivotally connected, a sectional porous mold suitably mounted on frame and adapted to open and close, and means for operating the same.
- 20 3. In an apparatus of the character described, a separable porous mold suitably mounted on a portable tong-like frame, a flexible pipe-line for compressed air opening 25 into said mold, and means for dislodging finished containers from said mold.
- 25 4. In an apparatus of the character described, a separable porous mold suitably

mounted on a portable tong-like frame, a valve-controlled flexible pipe-line for compressed air opening into said mold, and means for discharging finished containers from said mold.

5. In an apparatus of the character described, a portable frame comprised of sections pivoted together at their central portions, a separable porous mold mounted on said frame, said mold being adapted for the formation therein of containers by means of compressed air exerted against a mixture of moistened pulp held in said mold, means for opening and closing said mold, and means for dislodging and discharging the finished containers from said mold.

6. In an apparatus for forming containers from fibrous substances by the action of compressed air, a portable frame comprised of sections pivoted together, a separable porous mold mounted on said frame, means for admitting air under compression into said mold, and means for discharging the finished containers.

In testimony whereof I have hereunto affixed my signature.

WILLIAM S. REA.
